UNITED STATES PATENT OFFICE.

JAMES DURKIN, OF DENVER, COLORADO.

MECHANICAL PROMPTER.

1,081,220.

Specification of Letters Patent.

Patented Dec. 9, 1913.

Application filed November 23, 1912. Serial No. 733,178.

To all whom it may concern:

Be it known that I, JAMES DURKIN, a subject of the King of Great Britain, residing in the city and county of Denver, 5 State of Colorado, have invented a new and useful Improvement in Mechanical Prompters, of which the following is a specification.

My invention relates to mechanical 10 prompters for theatrical purposes wherein a plurality of annunciators placed within the footlight trough at the front of the stage, and controlled by the prompter behind the scenes, are adapted to exhibit to 15 the performer any line or lines of the manuscript or production which he has forgotten, and the object of my invention is to prompt an actor or performer in his lines from any one of the three general directions 20 in which the said performer or actor may be facing, viz. to the right, left or center of the stage, and it is the further object of my invention to provide means for controlling a plurality of mechanical prompters 25 from the desk of the regular prompter behind the scenes, also to illuminate the prompters momentarily when it is desired to prompt the actor.

The operation and construction of my invention may be more clearly understood by 30 reference to the drawings forming a part of this specification wherein like numerals and letters of reference refer to similar parts throughout the said specification and drawings in which—

Figure 1 is a plan view of the stage set for a production disclosing the mechanical prompters within the footlight trough at the front of the stage, the prompter's desk 40 for controlling the prompters within the footlight trough and the possible positions of three performers. Fig. 2 is an enlarged broken view of the footlight trough and the prompter's desk behind the scenes showing 45 the driving connection between the prompter's desk and the mechanical prompters within the footlight trough. Fig. 3 is a front view of one of the prompters within the footlight trough partly in section and with the cover removed therefrom disclosing the manner in which the rewinding drum is connected to the driving mechanism, also the clutch for automatically releasing the receiving cylinder and engaging 50 the reversing sprocket. Fig. 4 is a vertical section through the box showing the man-

ner in which the manuscript travels between the glass guides from one roll to another, the position of the lamp for illuminating the manuscript, and the spring tension plate 60 for maintaining a uniform tension on the receiving cylinder, clutch member and the reversing sprocket. Fig. 5 is a detailed sectional view through the center of the winding roll showing the hook for engaging the 65 forward end of the manuscript. Fig. 6 is a broken detailed view disclosing the forward end of the manuscript with a ring thereon adapted to be engaged by the hook on the winding roll. Fig. 7 is a sectional 70 view through the footlight trough and one of the mechanical prompters. Fig. 8 is a broken elevation of the driving connection between the prompter's desk and the driving mechanism of the mechanical prompters 75 within the footlight trough.

The present method of prompting actors who have forgotten their lines during a production is to have a prompter with a manuscript of the production stand just off stage 80 at a small desk, behind the proscenium arch, and call out the cue or required or forgotten lines to the performer. Quite frequently, in order to be audible to the performer, the lines which are called out are also audible 85 to the audience and generally has a detrimental effect on the production as well as the actor who has forgotten his lines.

It is the object of my invention to provide means which shall be invisible to the audience, controlled from the prompter's desk, and visible to the performer in any one of three directions which are generally assumed upon the stage, viz. right, left or to the center.

In Fig. 1 of the drawings I have indicated three performers as, for instance, A seated in a chair behind a table, B seated upon a sofa, and C standing slightly to the left of A. Were C to forget his lines, by 90 glancing in the direction indicated by the dot and dash line, which is the same direction in which he is already facing, his glance encounters that particular mechanical prompter indicated by the said line. 95 Were A to forget his lines it is only necessary that he glance to the centrally located mechanical prompter and B could take advantage of the mechanical prompter at the other end of the footlight trough which is 100 practically in front of him. In this way 105 any actor in any position generally assumed 110

on the stage may observe a mechanical prompter without perceptibly altering his position. It may also occur that one performer might intercept the line of vision between a mechanical prompter and an actor who has forgotten his lines, in which case the latter can easily direct his gaze, without altering his position very much, to one of the other prompters within the footlight trough. These prompters consist of a negative manuscript, that is to say, a roll of paper with a dark background and light transparent characters. The lines upon the manuscript within the prompter are invisible to the actor until the same has been lighted from within by the act of the prompter behind the scenes so that there will be no unusual light to attract the attention of the performers except when they have forgotten their lines.

The mechanical prompters are constructed and operated as follows:

A rectangular casing 1 having a glass plate 2 centrally located near the front portion thereof is provided with a winding roll 3 loosely mounted upon a continuous drive shaft 4 which is rotated manually by the prompter behind the scenes in a manner hereinafter more fully described, and a rewinding roll 6 which is secured to the rewinding shaft 7 as follows. The rewinding roll 6 is composed of a hollow sleeve having flanges 6' at the outer ends thereof, a center rod 8 is provided with a reduced threaded portion 8' at one end thereof which screws into the threaded socket 7' of the rewinding shaft 7 in such a manner that the said roll 6 is tightly secured between the shoulder 10 of a knob 11 and the annular flange 12 of the rewinding shaft 7. On the end of the rewinding shaft is a sprocket 14. A chain 15 running over this sprocket is engaged by the sprocket 16 loosely mounted upon the continuous drive shaft 4, between the bearing 17 and a clutch member 18 secured to the shaft 4. The sprocket 16 is provided with a clutch face 16' and the rewinding roll 3 is provided with a similar clutch face 3'. The clutch member 18 is secured to the drive shaft 4 by means of a transverse pin 4', rigidly secured to the drive shaft 4, which engages a spiral slot 18' in the said clutch member 18. When the drive shaft 4 is turned forward the action of the said pin 4' upon the slanting surface of the spiral slot 18', within the said clutch member 18, causes the said member 18 to recede from the clutch face 16' of the sprocket 16 and to engage the clutch face 3' of the cylinder 3. In order to facilitate the above action a friction plate 20 frictionally engages the upper half of the peripheries of the clutch member 18 and the hubs containing the clutch faces 3' and 16' and by reason of such friction upon said members,

prevents the rotation of any one of the said members until the said clutch member 18 has been acted upon by the pin 4', operating within the spiral slot 18' thereof, and positively engages the clutch face 3' toward which it is moving. A further function of the spring friction plate 20 is to prevent either roll from unwinding too rapidly and to keep either the sprocket 16 or the cylinder 3 in positive engagement with the clutch member 18, also to maintain a uniform tension on the manuscript. A lamp 22 within the box is provided for the purpose of illuminating the manuscript from behind, and is lighted momentarily by the prompter behind the scenes when it is desired to prompt the actor. The manuscript 23 passes from the rewinding roll over the guide roll 24 and between the glass plate 2 within the box 1 and a glass plate 25 within the cover 26 of the box 1, and over a second guide roll 27 to the winding roll 3. The forward end of the manuscript 23 is provided with a ring 23' adapted to be engaged by a hook 29 within a depression 31 of the winding roll 3. 90

The several prompters within the trough are operated from the prompter's desk 32 behind the scenes. The said prompter's desk 32 is similar in construction and operation to the prompters within the footlight trough excepting that the characters of the manuscript within the prompter's desk are typewritten and the corresponding portions of the mechanism proportionately reduced. Also the drive shaft 4 is fitted at the right hand end with a crank or handle 33 for rotating the same. The opposite end thereof is provided with a gear 34 meshing with a bevel pinion 35 at the upper end of a vertical shaft 36 which passes through the floor 37 of the stage and is provided at its lower end with a bevel gear 38 which meshes with a pinion 39 secured to the drive shaft 4 which operates the prompters within the footlight trough. The characters of the manuscript of the prompters within the trough are of such size and proportion as to be easily read from any portion of the stage, while the manuscript within the prompter's desk is of the usual sized type to be found in typewriters. Whenever the prompter turns the manuscript forward a line the same result must be produced simultaneously within the mechanical prompters of the footlight trough. In order to compensate between the difference in width of one typewritten line on the prompter's desk and one line of the larger characters within the footlight prompters the ratio between the gears 34 and 35 and the gears 38 and 39 is increased proportionately. In cases where there is a change of direction of the footlight trough, as shown in Fig. 2, I have provided universal joints 41 at the points in the drive shaft 4 where the change of direction 130

occurs. After the production is finished and the entire length of the manuscript 23 has been wound upon the roll 3, before the next performance is begun the manuscript must be rewound upon the roll 6. By turning the handle 33 backward, through the medium of the beveled gears and pinions 34 and 35 respectively, vertical shaft 36, beveled gear and pinions 38 and 39 respectively, the drive shaft 4 will be rotated in the opposite direction from that of winding up the manuscript and the pins 4', acting on the spiral slot 18', as hereinbefore described, will automatically disengage the clutch member 18 from the clutch face 3' of the winding roll 3 and cause the same to engage the clutch face 16' of the sprocket 16 and, by means of the sprocket chain 15, rewinding shaft 7 and rewinding roll 6, rewind the manuscript upon the rewinding roll. The mechanical prompters are now ready for the next performance.

It is obvious from the foregoing that I have provided means for prompting the performers on the stage that are controlled from the prompter's desk behind the scenes in such a manner that the said performers may observe the same without altering their positions or being exposed to the embarrassment of having their lines called from behind the scenes. I have also provided means for controlling and rewinding a plurality of mechanical prompters simultaneously, and for temporarily illuminating the said prompters.

I do not wish to confine myself to the precise construction herein but rather to avail myself of any modifications that may fall properly within the scope of my invention.

Having thus described my invention what I claim as new and desire to secure by Letters Patent is—

1. In a mechanical prompter the combination of a plurality of suitable hollow boxes each box having a winding and rewinding cylinder rotatably mounted therein; a clutch member secured to the winding cylinders; a transparent table between the cylinders; a transparent manuscript attached to each rewinding cylinder and adapted to travel over the transparent table; means for illuminating the transparent manuscript; a continuous shaft suitably mounted in bearings and running through each of the winding cylinders in each box; a sprocket loosely mounted, in each box, upon the said continuous drive shaft and adjacent to the cylinder thereon; a sprocket on the shaft of the other cylinder; suitable driving connections between said sprockets; a clutch member secured to the continuous drive shaft and adapted to engage the cylinder mounted thereon when said drive shaft is rotated in one direction and adapted to automatically release the cylinder and engage the sprocket when the

shaft is rotated in the opposite direction; and means for maintaining a uniform tension on the cylinders and sprockets.

2. In a mechanical prompter the combination of a plurality of suitable hollow boxes; a detachable rewinding cylinder rotatably mounted in each box and having a sprocket secured to the shaft thereof; a continuous drive shaft running through each box and having a plurality of clutch members secured thereto, one within each box; a winding cylinder having a clutch integral with one end thereof, and loosely mounted upon the continuous drive shaft and in each box; a transparent manuscript rolled upon the rewinding cylinder and secured to the winding cylinder; a sprocket in each box loosely mounted upon the drive shaft and adjacent to the clutch member; suitable driving connections between said sprocket and the sprocket on the rewinding cylinder; means for automatically engaging the winding cylinder when the shaft is rotated in a forward direction and for engaging the rewinding cylinder when the shaft is rotated in the opposite direction; and means for maintaining a uniform tension on the cylinders and sprockets.

3. In a mechanical prompter the combination of a plurality of suitable hollow boxes arranged at intervals upon a continuous drive shaft; a shaft having a sprocket at one end thereof rotatably mounted within each hollow box; a flanged cylinder detachably secured to each rotatable shaft; a second flanged cylinder within each box having a clutch integral with one end thereof and loosely mounted upon the continuous drive shaft; a sprocket in each box having a clutch member integral therewith and loosely mounted upon the continuous drive shaft; suitable connection between the sprocket on the continuous drive shaft and the sprocket on the rotatable shaft within the other end of the box; a clutch member having a spiral slot therein and loosely mounted, in each box, upon the continuous drive shaft; transverse pins secured to the continuous drive shaft and adapted to engage the spiral slots of the clutch member and cause the said member to be disengaged from the clutch integral with the sprocket; and means for retarding the rotation of the cylinder, sprocket or clutch member when the same are not positively engaged by the drive shaft.

4. In a mechanical prompter the combination of a plurality of suitable hollow boxes; a shaft having a sprocket at one end thereof rotatably mounted within one end of each box; a cylinder detachably secured to each shaft; a continuous drive shaft running through the opposite end of each box; a cylinder having a clutch integral with one end thereof loosely mounted in each box and

- upon the continuous drive shaft; a sprocket having a clutch member integral therewith loosely mounted in each box and upon the drive shaft; suitable driving connections between the sprockets on the drive shaft and the sprockets on the rotatable shafts in the opposite ends of the boxes; clutch members having spiral slots in the peripheries thereof and secured to the drive shaft between each sprocket and cylinder; transverse pins secured to the drive shaft and adapted to engage the spiral slots within the clutch members; and a friction plate adapted to engage the hubs of the receiving cylinders and sprockets and the clutch members and retard the rotation of said members until positively engaged by the driving shaft.
